REFLECTION DENSITOMETER

Perry Dwaine Hampton, Dallas, James R. Cox, Richardson, and Peter J. Warren, Dallas, Tex., assignors to Cosar Corporation, Garland, Tex.

Filed Apr. 30, 1973, Ser. No. 355,674

Term of patent 14 years

Int. Cl. D10—04

U.S. Cl. D32—2

Figure 1

Figure 2

Figure 3

Figure 4

Figure 5

FIG. 1 is a top, front, and left side perspective view of a reflection densitometer showing our new design;

FIG. 2 is a full front perspective view of FIG. 1;

FIG. 3 is a top plan view of FIG. 2;

FIG. 4 is a left side elevational view of FIG. 1; and

FIG. 5 is a right side elevational view of FIG. 1.

The back and the bottom are plain and unornamented. We claim:

The ornamental design for a reflection densitometer, as shown and described.
